FREE-PISTON GAS HEATER SYSTEM

The present invention relates to gas heaters, and more particularly, to improvements in means for producing a continuous flow of hot gas from a supply at room temperature. It is known to produce gas heating by using flow restrictors. In the present invention a reciprocating piston acts on a supply of gas from the outlet of a check valve to intermittently transfer energy to the gas which is driven back and forth through the restrictors and out through an outlet. This invention is especially concerned with a means for driving the piston, in order to provide an efficient, high power system capable of producing a substantial flow of gas at 1,500° to 2,000° K.

Briefly, my invention comprises the combination of a flow restrictor heater to heat a working gas, a mechanical interface between the heater and a driver, and a valving mechanism using a driver gas to efficiently drive the interface.

This invention will be more fully understood by reference to the following detailed description of a preferred embodiment, and to the accompanying illustrative drawings.

In the drawings,

FIG. 1 is a schematic diagram of the broad form of the present invention.

FIG. 2 is a pressure-distance graph showing transfer of energy from the driver gas to the working gas in the present system.

FIG. 3 is an enlarged schematic view showing in more detail a preferred valving arrangement for the system of FIG. 1.

FIG. 1 shows the general form of the present invention. Here a piston member 1 operates in a compression chamber 2, acting upon a working gas in the right-hand end of chamber 2. The working gas enters this end through a check valve 4 supplied from a working gas inlet 5. The inlet gas can be at room temperature. A first flow restrictor 6 in the end of compression chamber 2 leads into a second chamber 7, and a second restrictor 9 leads from second chamber 7 to a third chamber 10. An exit orifice 11 is connected to the outlet end of third chamber 10.

This forms a restrictor type or orifice type gas heater. As piston 1 moves to the left, low pressure in the right end of compression chamber 2 admits working gas through the check valve 4 into the compression chamber 2. When piston 1 moves to the right, mechanical work is exerted on the working gas, heating it and pushing it through the first restrictor 6. As the reciprocating piston continues, the working gas is sloshed back and forth through the restrictors and the oscillating flow is smoothed out until the gas is driven through the exit orifice 11 at a substantially constant rate of flow, and at an elevated temperature.

The reciprocating piston 1 may be either a free piston or connected to an operating linkage, such as a connecting rod and crankshaft for example. In the present case, it is preferred to drive the piston in a "forward" direction by a driver gas supplied through a valving arrangement as shown broadly in FIG. 1. A four-port valve 14 has one port connected to a chamber inlet 15. Three other valve ports are respectively connected to a driver gas supply 16, an intermediate chamber 17, and an exhaust passage 19.

The valve 14 has two operating positions. In position I, a first path is open between the driver gas supply 16 and the intermediate chamber 17, and a separate path is open between the compression chamber 2 and the exhaust passage 19. In valve position II, a single open path is provided between the intermediate chamber 17 and the compression chamber 2. The driver gas supply 16 comprises a source of high pressure gas. The piston member 1 forms the mechanical interface between the driver gas and the working gas.

The valve 14 is in position I as the piston 1 is moving to the left. This allows exhausting of the driver gas space on the left-hand side of piston 1 and filling of the intermediate chamber 17 from the driver gas supply 16. When piston 1 nears or reaches the left end of its travel, the valve 14 is forced to position II, where the piston 1 is driven forward (to the right) by the working gas stored in the intermediate chamber 17. At or near the right end of piston travel, the valve 14 returns to position I, again allowing exhaust of driver gas from compression chamber 2 and refilling of the intermediate chamber 17.

Any suitable valve timing or synchronizing means may be utilized, based on piston position or pressures at different locations in the valve system. Preferably, the piston itself should be used in the timing control of the valve, so that the valve operation is correctly synchronized with piston operation.

A preferred valve mechanism is schematically shown in FIG. 3. A valve housing 20 mates with and is attached to the driver gas end of the compression chamber 2 containing a free piston 1a. Piston 1a has a cylindrical plug or nose portion 21 centered at its left end, the diameter of nose 21 being smaller than the main piston. A partially hollow, sliding valve spool 22 is carried in the right-hand end of housing 20, and a counter-pressure chamber 24 is to the left of the valve spool 22. An external circumferential spool groove 25 surrounds one end of spool 22, and a series of radial operating ports 26 circles the hollow end of spool 22 and connects the outside of the spool to its interior. The interior diameter D of spool 22 is only slightly larger than the diameter of the piston nose 21.

An exhaust port 27 (or series of ports), a supply port 29, a filling port 30 and an inlet port 31 are provided in the valve housing 20 as shown. In the right-hand position shown, spool 22 is against a right-hand stop 32 provided by the internal diameter of the compression chamber 2. In this position, the inlet port 31 is open to the filling port 30 through the spool groove 25, the supply port 29 is closed, and the exhaust port 27 is open to the spool interior and to the compression chamber 2 by the spool operating ports 26. At the left-hand position, spool 22 is against a left-hand stop 34 provided by the internal diameter of the counter-pressure chamber 24. In this left position, the only flow path through the valve is from the supply port 29 through the operating ports 26 to the interior of the spool 22 and the compression chamber 2.

Exhaust port 27 leads to the atmosphere. An intermediate chamber 17a is connected to the supply port 29 and filling port 30. A driver gas supply line 35 is connected to the inlet port 31. A counter-pressure gas line 36 is connected to the counter-pressure chamber 24, and means are preferably provided to maintain a

constant predetermined pressure in this line 36. Such means may include a definite small flow of counter-pressure gas in through a restrictor valve 37 and out through a bleed valve 39, with the counter-pressure gas line 36 connected to a point between the latter two valves. A pressure gage 40 may also be connected to this same point.

Operation of the valve system of FIG. 3 will be explained with first assuming a piston movement to the left, with the valve spool 22 being held in the (exhaust) position shown by pressure in the counter-pressure chamber 24. The free piston 1a has bounced back from the relatively high working gas pressure at that time and hence is travelling rapidly. When the piston nose 21 enters the interior diameter of the valve spool 22 or even before, a back pressure builds up because of trapped gas in the annular space between the main body of the piston and the outer portion of the spool. Two results of such back pressure are (1) the valve spool 22 is shifted to its left-hand position against the constant pressure in counter-pressure chamber 24, and (2) the piston 1a bounces back in the right-hand direction without touching the spool 22.

When piston 1a thus bounces to the right, driver gas from the intermediate chamber 17a is admitted through the spool operating ports 26 to the piston 1a. The high pressure driver gas maintains the valve spool 22 in its left-hand position and also drives the piston rapidly to the right, to thus act on the working gas which has been admitted through the check valve 4 (FIG. 1) while the piston was at the left side.

When piston 1a nears the right-hand end of its travel, the intermediate chamber 17a has been emptied to the point where the compression chamber pressure to the left of the piston has decreased sufficiently so that counter-pressure on the left of the valve spool 22 shifts the spool to the right. Also, the piston will bounce back to the left against the relatively high working gas pressure in its lowered volume. In the right-hand spool position, the intermediate chamber 17a is refilled and the driver gas exhausts. The force of the exhaust gas pressure on the spool is less than the force of the counter-pressure gas on the spool, so that the spool remains in its right-hand position during this portion of the cycle. The cycle is now completed and the system continues operation in repeat fashion.

In order to start up the present system as described, a starting apparatus as shown in FIG. 3 may be used. A container 41 of a starting gas at a desired pressure is provided. In an outlet line from this container 41 is placed a control valve 42 having a vacuum line 44 or line of low pressure connected to one port and a start gas delivery line 45 connected to an outlet port. The delivery line 45 is routed through a passage 46 in the compression chamber wall to a point at the interior which is between the piston 1a and the valve spool 22. This interior point is in communication with the annular space around the piston nose 21 referred to before, when the piston is at the left-hand end and the spool 22 is in its right-hand position.

Before starting the operation, the control valve 42 is turned to have the delivery line 45 connected to the low pressure line 44. Gas is thus withdrawn from between the spool 22 and piston 1a. The driver gas, working gas, and counter-pressure gas are all supplied

to their respective inlets, and the intermediate chamber 17a therefore becomes filled and pressurized. A certain pressure is also initially built up by the working gas behind the restrictors 6 and 9, thus aiding in moving the piston to its starting position and also charging the working gas volume in the compression chamber to form a cushion for the piston on its first stroke.

At the desired moment of starting, the control valve 42 is turned from the vacuum position, through the pressure position, to a closed position. A momentary surge of starting gas is thereby introduced which is sufficient to shift the valve spool 22 to the left and the piston to the right. This opens the supply port 29 for the driver gas in the intermediate chamber 17a and operation continues automatically.

FIG. 2 shows in a very general way the exchange of energy between the driver gas and the working gas. The driver gas is supplied from a high pressure source which may be as much as 1,500 psi for example. It may initially be at room temperature. The working gas may also be initially at room or ambient temperature, but the initial pressure need be only high enough to insure a continuous flow outward from the delivery nozzle 12, as for an air supply to a high-enthalpy wind tunnel for example. In a high power system of the type disclosed herein, the working gas may be heated to a temperature of 1,000° K or higher. The frequency of oscillation of the free piston may be about 30 to 100 cycles per second, for example. Of course the end-most portions of the compression chambers can have jacketed walls for pre-heating of the working gas and consequent cooling of the chamber walls. Further, the working gas for the input can be taken from the output after its utilization, in a closed-circuit path, for continued recirculation and higher temperature, with or without intercooling.

As further shown in FIG. 1, an alternate embodiment to eliminate the check valve 4 is a re-located working gas inlet 47 placed to the left of the original inlet. In this modification, the piston 1 performs its own check valve function when it closes the inlet 47 during the compression stroke. Working gas will be admitted when the inlet is uncovered during piston travel to the left, and thus no check valve is needed.

Although the reciprocating piston could be driven in many ways, the present free-piston arrangement using a compressed driver gas with proper timing relation and wherein the "reverse" piston stroke is a pure bounce from working gas located between the piston and the first flow restrictor, is preferred because of its simplicity and efficiency. The energy transfer from the pressurizing source of the driver gas to the working gas can typically be made greater than 50 percent efficient. The free piston exhausts the driver gas to the atmosphere without any substantial entropy increase, e.g., in contrast to the case for shock-tube-devices.

The flow restrictors 6 and 9 may be simple plates having one or more orifices. Two separate restrictors separated by the secondary chamber 7 are disclosed herein, but the invention of course encompasses one, two, or three or more series restrictors.

The piston member 1 or 1a disclosed herein is a preferred interface between the driver and working gases, but it could be possible to use a much larger diameter of compression chamber with diaphragm type

device in place of an actual piston. Hence a diaphragm is deemed to be an equivalent of a piston for the purpose of defining this invention.

While in order to comply with the statute, the invention has been described in language more or less specific as to structural features, it is to be understood that the invention is not limited to the specific features shown, but that the means and construction herein disclosed comprise the preferred form of putting the invention into effect, and the invention is therefore claimed in any of its forms or modifications within the legitimate and valid scope of the appended claims. 10

What is claimed is:

1. A gas heater system comprising:

- a. a compression chamber having a working gas inlet, 15 a flow restrictor and an outlet;
- b. a free piston member in said compression chamber, said piston being free to be operated upon only by gas pressures in a forward and reverse direction, said working gas inlet and said restrictor being on the same side of said piston;
- c. intermittent driver gas supply means, including 20 mechanical valving means, connected to said compression chamber on the other side of said piston;
- d. a separate intermediate driver gas chamber;
- e. said valving means having a first position where 25 (1) a flow path is open between a pressurized driver gas supply and said intermediate chamber, and (2) a separate flow path is open between said compression chamber and an exhaust outlet, and having a second position where a flow path is open only between said intermediate chamber and said compression chamber; and
- f. synchronizing means between said piston and said 30 valving means.

2. Apparatus in accordance with claim 1 wherein said intermediate chamber is sized to have its pressure substantially reduced by transferring gas from it to said compression chamber. 40

3. A gas heater system comprising:

- a. a compression chamber having a working gas inlet, 45 a flow restrictor and an outlet;
- b. a piston member in said compression chamber, said working gas inlet and said restrictor being on the same side of said piston;
- c. intermittent driver gas supply means including mechanical valving means, connected to said compression chamber on the other side of said piston;

d. said valving means comprising a valve housing, and a sliding valve spool in said housing;

e. an intermediate chamber;

f. means connecting said valving means to a source of pressurized driver gas;

g. porting means between said driver gas source, intermediate chamber, valve spool and compression chamber for filling said intermediate chamber and exhausting said compression chamber in one spool position, and for discharging said intermediate chamber into said compression chamber in a second spool position; and

h. synchronizing means between said piston and said valving means.

4. A gas heater system comprising:

- a. a compression chamber having a working gas inlet, a flow restrictor and an outlet;
- b. a piston member in said compression chamber, said working gas inlet and said restrictor being on the same side of said piston;
- c. intermittent driver gas supply means, including mechanical valving means, connected to said compression chamber on the other side of said piston;
- d. said valving means comprising a valve housing attached to said compression chamber with the interior of said housing opening into said compression chamber, and a valve spool sliding in said housing between two positions;
- e. an intermediate chamber;
- f. porting means in said spool and housing for filling said intermediate chamber from a source of pressurized driver gas and exhausting said compression chamber in a first spool position next to said compression chamber, and for discharging said intermediate chamber into said compression chamber in the other spool position away from said compression chamber; and
- g. synchronizing means between said piston and said valving means.

5. Apparatus in accordance with claim 4 including timing means comprising a counter-pressure chamber behind said spool from said compression chamber, and means for maintaining a substantially constant counter-pressure, whereby the counter-pressure maintains said spool in said first position during the exhaust stroke of said piston and the driver gas pressure maintains said spool in said other position, overcoming said counter-pressure, during the forward stroke of said piston.
